(57) **CLAIM**

I claim the ornamental design for a back cover for a handset, as shown and described.

DESCRIPTION

FIG. 1 is a bottom plan view of the back cover for a handset; FIG. 2 is a right side view thereof; FIG. 3 is front view thereof; FIG. 4 is a left side view thereof; FIG. 5 is a perspective front view thereof; FIG. 6 is a bottom plan view of a second embodiment of the back cover for a handset of FIG. 1; FIG. 7 is a left side view thereof; FIG. 8 is a front view thereof; FIG. 9 is a right side view thereof; and, FIG. 10 is a perspective front view thereof. The broken line showings are for illustrative purposes only and form no part of the claimed design.
